UNITED STATES PATENT OFFICE.

FRANCIS I. HOEFLER, OF CINCINNATI, OHIO, ASSIGNOR TO THE CINCINNATI COFFIN COMPANY, OF CINCINNATI, OHIO, A CORPORATION OF OHIO.

COFFIN-HANDLE.

No. 826,033.

Specification of Letters Patent.

Patented July 17, 1906.

Application filed July 24, 1902, Serial No. 116,814.

To all whom it may concern:

Be it known that I, FRANCIS I. HOEFLER, a citizen of the United States, and a resident of the city of Cincinnati, in the county of Hamilton and State of Ohio, have invented certain new and useful Improvements in Handles for Coffins, Caskets, and other Articles, of which the following is a specification.

My invention relates to certain new and useful improvements in the construction of the attachments or ears for supporting the handle bar or piece and for connecting said bar to the article or thing wherewith the handle is to be used.

The several features of my invention and the various advantages resulting from their use conjointly or otherwise will be apparent from the following description and claims.

In the accompanying drawings, making a part of this specification and in which similar letters of reference indicate corresponding parts, Figure 1 is a front elevation of a handle and attachments embodying my invention. Fig. 2 is a vertical central section taken from front to rear through the attachments for supporting the handle-bar. Fig. 3 is a view in perspective of the skeleton frame which is to be attached to the article or thing with which the handle is to be used. Fig. 4 is a view in perspective of the skeleton frame which is to be connected directly to the handle-bar. Fig. 5 is an elevation of the frames, respectively, shown in Figs. 3 and 4, but showing them pivotally connected, as when used.

It is to be understood that the frames are shown in Figs. 3, 4, and 5 as they appear when stripped of their ornamental soft-metal incasements.

I will now proceed to describe my invention in detail. In thus describing it I will specify its use in connection with a coffin or casket, premising this description will sufficiently illustrate its application to other articles and its use therewith.

A indicates the handle-bar constructed in any desired manner and of any suitable material. To properly sustain this handle-bar, two sets (a pair) of attachments are desirable. B indicates the bracket-frame adapted to be secured to the coffin, casket, or other article. This bracket-frame B consists of the side bracket-arms B² B² and the base plates or parts B³ B³. As this frame is made of one

piece of metal, usually of one blank sheet of 55 metal duly outlined by cutting and then stamped or pressed to final shape, the front end B⁴ of the bracket is where the front bend of the metal occurs and where the two bracket-arms B² B² are united. Before the 60 blank of the bracket-frame is thus bent to shape the pivot-holes B⁵ are punched therein. The upper portion of the base-plates B³ are formed into shoulders B⁶, one for each plate B³. It is to be understood that the 65 plate B³ present on the right-hand side of Fig. 3 is similar to the one fully shown on the left hand of this figure. The plates B³ are each provided with an opening B⁷. In use each of these openings receives a screw or 70 bolt, whereby the bracket is securely fastened to the coffin. The handle-hanger frame is also preferably made from a piece of sheet metal, first cut so as to have a proper outline and then having the holes which are 75 to receive the pivot punched. The plate thus outlined is bent to shape, usually by suitable dies. When properly shaped, this hanger C is as follows: It has a main or shank portion C² hollow on one side—namely, on 80 that side which is underneath when the hanger is elevated. The other side or back C¹⁰ of the shank C² is, if seen in cross-section, curved. The curvature is well illustrated in Fig. 4. Near one end of the shank occur the 85 holes C³ C³, one in each lip or side of the shank. Beyond these holes C³ C³ from each lip of the shank projects rearward at an angle to the longitudinal line of the shank the bearing- 90 pieces, each indicated by the character C⁴. The other end of the shank terminates in 95 means for holding—that is, grasping—the handle A. These means consist, essentially, of the embracing-piece D. Where the handle is rectangular in shape at the lower corners, the piece D, formed as shown by heavy lines in Fig. 5, has a square corner C⁸, and this variety of the piece D is indicated by the character C⁵. Where the handle is round, this variety or species of the piece D is 100 formed as shown by heavy lines in Fig. 4, and by the dotted lines at the lower end of the hanger in Fig. 5, and is indicated by the character C⁶. In both varieties there are 105 preferably present, extending from the rear or under side of the shank, the hook-shaped extensions C⁷ C⁷.

In the instance of a handle having when

dropped square bottom corners, as mentioned, the upper part of the handle where it is embraced by the hanger is in cross-section somewhat convexly curved, and the adjacent surface of the edge—namely, at C⁹—is correspondingly concavely curved. Such curvature operates to lock the handle so that it cannot roll out of the open side of the piece D after having been slipped longitudinally ¹⁰ therein.

The hanger C is pivoted to the bracket B by a pivot E, passing through the holes C³ of the hanger and the holes B⁵ of the bracket-arm, substantially as shown in Fig. 5.

¹⁵ The hanger-frame C is duly combined with an enveloping casing of soft metal or other suitable material, such as hard rubber or the like. The soft metal, &c., can be molded or shaped so as to bear ornamental forms. One ²⁰ form of ornamentation is shown on the hanger illustrated in Fig. 1. The hanger, consisting of the frame C with the casing of soft metal or other material, is indicated by the letter N. The bracket B is also combined with an ornamental casing M², of soft metal or hard rubber, &c. One form of such casing is shown in Fig. 1. The combination ²⁵ of the bracket B with the ornamental casing M² is indicated by the letter M. In Fig. 2 ³⁰ the combination of the hanger N and its soft-metal casing N² and of the bracket M and its soft-metal casing M² are illustrated.

To stiffen the central portion of the shield or escutcheon forming an ornamental part of ³⁵ the bracket-arm, a projection M³ is present, extending from the front face of the shield rearwardly to the coffin-wall. This projection M³ serves to prevent the shield from being crushed in at the center.

⁴⁰ The bracket-arm B and the hanger C are of a construction which is simple, easily effected, and cheap in manufacture. Their mode of construction confers all necessary stiffness and strength upon the connection of the handle to the coffin or other article. The form of ⁴⁵ this bracket and the form of this hanger are adapted to receive ornamental casings. The tubular form of the part C² of the hanger confers great strength upon the shank of the ⁵⁰ hanger, especially in resisting side thrust and torsional strain.

It has been found by experience that heretofore all of the handles broken have given way at the point Z, Fig. 1. This was due to ⁵⁵ the weakness of the hanger there. Frequently when the coffin or casket is being passed through a narrow doorway the entire weight will rest upon one handle upon each side, on which occasions such handles are ⁶⁰ often subjected to a wrench or a wrenching strain. Then the handle is broken there. My formation of the shank by constructing it with a double wall and curved (tubular) back confers extra strength upon the handle

where it was heretofore weak and prevents ⁶⁵ breakage of the handle at that part of it.

What I claim as new and of my invention, and desire to secure by Letters Patent, is—

1. In a handle for coffins and the like, a bracket consisting of a horizontal part and ⁷⁰ two arms B² B² extending at right angles therefrom said arms being in contact with each other and joined together at their outer ends and each arm having the pivot-hole B⁵ adjacent said outer end, and a connecting ⁷⁵ hanger-frame having a back C¹⁰ and duplicate side pieces C², each side piece being provided with a pivot-hole C³, said sides and back of the hanger-frame embracing the arms B² B² and a pivot-pin passing through the holes B⁵ and ⁸⁰ C³ to connect the parts together.

2. In a handle for coffins and the like, a bracket-arm B, consisting of the symmetrical halves united at the front B⁴, each of the duplicate arms B² having the pivot-hole B⁵, ⁸⁵ each of the plates B³ having the wall-shoulders B⁶ and the eyes B⁷, and the hanger-frame C having a back C¹⁰ uniting duplicate side pieces C², each side piece being provided with a pivot-hole C³ and a projection C⁴ beyond the pivot-hole C³ and at the other end provided with the extension D adapted to embrace the handle-bar and having the hooked extension C⁷, for confining the handle-bar, the conjoint arms B² of the bracket ⁹⁰ located between the sides C² of the hanger and pivotally connected by a pivot common to the holes C³ and the holes B⁵, the projections C⁴ being adapted to rest upon the shoulders B⁶, when the handle-bar is raised, ¹⁰⁰ substantially as and for the purpose specified.

3. In handles for coffins and the like, a handle-hanger frame C, having a back C¹⁰ uniting duplicate side pieces C², each side ¹⁰⁵ piece being provided with a pivot-hole C³ and a projecting inclined arm C⁴ beyond the pivot-hole, and at the other end provided with the extension D adapted to embrace the handle-bar, and a bracket-arm adapted to be ¹¹⁰ received between the sides C², C², and be pivoted to the same at C³, C³, and having widely-separated wall-shoulders against which the projections C⁴, C⁴, respectively impinge when the handle-bar is raised, substantially ¹¹⁵ as and for the purposes specified.

4. In a handle for coffins and the like, a bracket-arm B, consisting of the symmetrical halves united at the front B⁴, each of the duplicate arms B² having the pivot-hole B⁵, ¹²⁰ each of the plates B³ having the shoulders B⁶ and the eyes B⁷, and the hanger-frame C having a back C¹⁰ uniting duplicate side pieces C², each side piece being provided with a pivot-hole C³ and a projection C⁴ beyond the pivot-hole C³ and at the other end provided with the extension D adapted to embrace the handle-bar, the conjoint arms B² of the

bracket located between the sides C² of the hanger and pivotally connected by a pivot common to the holes C³ and the holes B⁴, the projections C⁴ being adapted to rest upon the 5 shoulders B⁶, when the handle-bar is raised, substantially as and for the purposes specified.

5. A handle having an escutcheon-plate for attachment to a casket or coffin, and 10 formed with a socket to receive the ends of a swinging arm, and with lugs at the sides of the socket to receive the ends of a pivot-pin, said escutcheon-plate being formed from soft metal, in which is bedded a hard-metal 15 reinforce, consisting of two parallel arms united at the front and extending rearward, and there respectively united to the flat vertical wall-pieces B³, B³, each of said pieces extending outwardly at right angles to the first- 20 named arms, and each carrying a shoulder, at the wall, the plane of the rear side of these shoulders coinciding with the plane of the rear side of the escutcheon, these wall-pieces being provided below with perforated lugs 25 embedded in the escutcheon-plate, the two parallel arms being covered with an extension of the soft metal of the escutcheon, in combination with a swinging arm, composed of hard metal, formed into two parallel sides 30 united above, and terminating in separated projections beyond the pivot-openings thereof, this swinging arm provided with a curved end, for the reception of the hand-bar, this swinging arm being covered with soft metal, 35 the hard-metal reinforce of the escutcheon-plate entering within the adjacent ends of the arm and connected thereto by a pivot-pin, the free ends of the projections of the swinging arm being adapted to respectively 40 rest upon the respective shoulders of the hard-metal wall-reinforce, when the swinging

arm is lifted into use, substantially as and for the purposes specified.

6. In a handle for coffins and caskets, a swinging arm, an escutcheon-plate for attachment to a casket or coffin, and formed with a socket to receive the two rear ends of the swinging arm, and with lugs at the sides of the socket to receive the ends of a pivot-pin, said escutcheon-plate being formed from soft metal, in which is bedded a hard-metal reinforce, consisting of two parallel arms united at the front and extending rearward and then provided with the flat vertical wall-pieces, each extending outwardly at right angles to the first-named arms, and each carrying a shoulder, at the wall, these wall-pieces having perforated lugs, embedded in the escutcheon-plate, the said two parallel arms being covered with an extension of the soft metal of the escutcheon, in combination with a swinging arm, composed of hard metal, formed into two parallel sides united above, and terminating in separated projections at the end nearest the escutcheon, the outer end 60 of this swinging bar being provided with a curved end for the reception of the hand-bar, this swinging arm being covered with soft metal, the hard-metal reinforce of the escutcheon-plate located between the projections of the swinging arm, and beyond the 65 said projections pivoted to the said arm, the free ends of the projections of the swinging arm being adapted to impinge upon the adjacent parts of the reinforce first aforementioned, when the swinging arm is lifted, substantially as and for the purposes specified. 70

FRANCIS I. HOEFLE.
